UNITED STATES PATENT OFFICE.

WILLIAM L. McLEVOY, OF WORCESTER, AND ARTHUR HUBBARD, OF LEOMINSTER, MASSACHUSETTS.

LIGHT FOR TRANSMISSION LOCKS.

Application filed May 11, 1927. Serial No. 190,593.

This invention relates to the provision of means for supporting a light in position to illuminate the transmission lock of an automobile.

5 The principal objects of the invention are to provide a light in proper location for illuminating the lock; to provide a small switching means for connecting it to a source of current; to provide a casing which 10 is shaped properly to slip down over the transmission case cover and fit the same accurately so as not to take up any unnecessary space, on which casing the light support is located, and to provide a casing with a 15 container for a battery for operating the light or for a current reducing means for connection with the wiring of the car.

The invention also involves the construction of the device as a part of the transmission case cover which projects up above 20 the floor of the car and carries the shift lever.

Other objects and advantages of the invention will appear hereinafter.

25 Reference is to be had to the accompanying drawings in which

Fig. 1 is a perspective view of a preferred form of this invention shown applied in proper position in the car to cover the lock and illuminate it;

Fig. 2 is a central longitudinal sectional view of the sheet metal casing;

Fig. 3 is a transverse sectional view on enlarged scale on the line 3-3 of Fig. 1;

30 Fig. 4 is a side view of another form of the invention in which it is integral with the transmission case cover ordinarily employed in the car;

Fig. 5 is a front elevation of the same;

40 Fig. 6 is a sectional view on the line 6-6 of Fig. 5; and

Fig. 7 is a plan.

In some makes of automobiles the transmission lock is located out of range of the 45 dash lights and dense shadows are thrown on it by the parts projecting above it. It is customary for many drivers to leave their cars unlocked rather than go to the trouble of lighting a match or feeling for the lock in the dark. This obviously results in danger of theft.

The form of the invention shown in the first three figures comprises a casing 10 which, when shaped to fit the transmission case cover of one type of Chrysler car, has a

conical portion at the front which is merged with a substantially rectangular portion 11 at the rear. This case is provided with an opening 12 at the top for the shift lever 13. The ball 14 on the lever fits in a rounded top 60 on the casing 10, just under this opening. This casing is made long enough to extend down through the floor as indicated in dotted lines in Fig. 1. The portion 11 of the casing is shaped to surround the lock 15 and it has a horizontal flange 16 resting on the top of the lock. At the rear of the conical portion it is extended out with parallel sides and is provided with a chamber 17 for an electric lamp 18. The walls of this chamber 70 are a part of the casing 10. It is provided with a hinge cover 19 and with a glass or isinglass rear wall 20 so located that the light will throw its rays directly on the top of the lock. 75

A wire 21 comes into the side of the casing and is connected with a strip of spring brass 29 which extends across to where it is held in an insulating socket 22 on a projection or bracket 23 in the casing. This strip has a bare portion provided with two bends 24 and 25 reversely directed. The cover 19 of this chamber is provided with a slide 26 having an operating handle 27 and an insulated wedge 28 on the bottom which constitutes the switch. When moved over from the left to the right, as shown in Fig. 3, the bottom of this wedge engages and forces down the upward projection 24 and forces the lower projection 25 into contact with the base contact of the lamp so as to make an electrical connection. When the switch handle 27 is moved back, the natural resiliency of the strip 29 will raise the projection 25 off the lamp contact. 85

The current can be supplied from a battery 30 located in a box 31 formed on the side of the casing and provided with a cover 32 or can be supplied from the battery of the car. The bottom of this box forms a 100 gauge to rest on the floor of the car to control the depth of the casing in the car. This furnishes a means by which the existing mechanism of a car can be provided in a simple and convenient way with means for illuminating the lock. It is not every car 105 that needs it, but where the car is so constructed that the lock is invisible at night, this is a very important attachment. The drivers of such cars have a tendency to 110

- 2
leave them unlocked rather than go to the trouble of finding the keyhole in such an inaccessible place. The lamp and battery will last a long time because it is lighted only 5 for an instant while the car is being locked or unlocked. The casing will be made to fit the particular mechanism of each separate car and the particular shape illustrated is formed for one particular one.
- 10 In the form shown in Figs. 4, 5, 6 and 7 the transmission case cover 40 is provided with an integral hollow projection 41 which provides a chamber 42 for the lamp which is located and operates exactly as in the other 15 case. Here the box 43 on the side is also integral if desired, and is for the purpose of receiving a resistance to reduce the current and voltage to make it suitable for a small lamp, such as used in this place. Other features are very similar to those described in 20 connection with the first sheet of drawings. It will be seen therefore that the invention, broadly speaking, can be applied to a car already made by means of the sheet metal casing 25 described, and that it can be applied to a car in the process of manufacture by the means shown on the last sheet of drawings. The difficulties above mentioned are avoided in either case.
- 30 Although we have illustrated and described only two forms of the invention we are aware of the fact that changes can be made therein by any person skilled in the art without departing from the scope of the invention as expressed in the claims. Therefore, we do not wish to be limited to the exact 35 form shown, but what we do claim is:—
1. As an article of manufacture, a hollow transmission case cover having a space 40 shaped for receiving a part of the shift lever of an automobile, said cover having a transmission lock located at the rear thereof, a chamber located in front of the lock and above it and having a transparent rear side 45 extending upwardly from the front of said lock, a light in said chamber adapted to illuminate the top surface of the lock, an electric circuit for supplying the light with current, and a switch for making and disconnecting the contact.
2. In a casing for an automobile transmission case cover, the combination with a sheet metal casing fitting said cover in the front and having a horizontal rear projection fitting 50 all around the transmission lock, said casing having a chamber at the rear with a vertical transparent panel projecting up from the top of the lock, and an electric lamp in the chamber.
3. In a casing for an automobile transmission case cover, the combination with a sheet metal casing fitting said cover in the front and having a rear projection fitting around the transmission lock, said casing having a chamber at the rear with a transparent panel 55 projecting up from the vicinity of the lock, an electric lamp in the chamber, a flexible conducting strip for the lamp having an upward projecting at one side and a downward projection on the other, a slidable switch 60 having an inclined lower edge adapted to engage the upward projection and force the downward projection into contact with the lamp contact to supply current therethrough, the switch being movable backwardly to allow the strip to be disconnected by its normal resiliency.
4. In a casing for the transmission case cover of an automobile, the combination with a casing having a conical portion at the front 65 for engaging said cover and a substantially rectangular portion at the rear extending to a lower elevation for receiving the transmission lock therein and having an opening 70 therethrough through which the lock can be seen and the key inserted, the conical portion having an opening at the top for the reception of the shift lever, and a chamber in said casing containing means for illuminating the top of the lock.
5. In a casing for the transmission case cover of an automobile, the combination with a casing having a front portion for enclosing said cover and a substantially rectangular portion at the rear extending to a lower elevation 75 for receiving the transmission lock therein and having an opening therethrough at the top through which the lock can be seen and the key inserted, a chamber in said casing containing means for illuminating the top of the lock, and a box on the outside of the casing for containing means to supply the illuminating means with power.
- In testimony whereof we have hereunto affixed our signatures.

WILLIAM L. McEVOY.
ARTHUR HUBBARD.
